RAILWAY CAR COUNTING SYSTEM

Benjamin Mishelevich, Pittsburgh, Pa., and Sih Hsuiin Tsiang, Morristown, N.J., assignors to Westinghouse Air Brake Company, Wilmerding, Pa., a corporation of Pennsylvania

Filed May 11, 1956, Ser. No. 584,208

9 Claims. (Cl. 246—122)

Our invention pertains to a railway car counting system and more particularly to a system for indicating the fullness of the storage tracks in a railway classification yard.

This invention is an improvement upon that disclosed in our copending application for Letters Patent of the United States, Serial No. 564,027, filed February 7, 1956, for a Car Counting System.

In the development of automatic operation of railway classification yards, particularly speed control systems for the car retarders used in such yards, it has been found necessary to include, among the various factors to be considered, a measurement of the fullness of each of the storage tracks in the yard to which the railway cars may be routed. This information is used to assist in selecting or computing the speed at which the cars should leave the several car retarders. In other words, this factor helps to determine how fast a car or cut of cars should move out of a car retarder, particularly the final retarder in any route, in order to couple at the proper speed with the cars already standing in the designated storage track. This factor enters into the computations by providing a measurement of the distance yet to travel for the particular car in question. The required accuracy of this track fullness factor depends upon the degree of automatic operation of the final retarders. When operation of the speed control system at the final retarder is to be completely automatic in determining the leaving speed and controlling the retarder pressure to obtain that leaving speed, a high degree of accuracy is required in each factor used, including the track fullness factor. In other words, the track fullness information furnished must be as accurate as is possible to obtain. The system disclosed in the previously mentioned copending application does not provide a particularly high degree of accuracy of the track fullness factor since it is intended primarily for use when completely automatic operation of the final car retarders is not contemplated.

It is accordingly an object of our invention to provide an improved car counting system for railway classification yards.

Another object of our invention is to provide an improved system of indicating the fullness of the various storage tracks in a railway classification yard.

Still another object of our invention is to provide an improved means in a railway classification yard to count the actual number of cars entering each storage track.

A further object of our invention is to provide an improved track fullness indication using portions of the automatic switching system of a railway classification yard to record each car in the counting device associated with the proper track.

Other objects and features of our invention will become apparent from the following specification when taken in connection with the accompanying drawings.

In practicing our invention, we provide a counting device for each storage track in the railway classification yard, these devices being of the type which advance one

2

count during each period of energization. The counter to be energized at any particular time is selected by repeaters of the switch control storage relays in the automatic switching system in order that each count may be associated with the proper track. In other words, at the initial switch leading to a group of storage tracks in the classification yard, each switch control storage relay in the final route storage bank associated with this initial switch is provided with a repeater relay. In the first species of our invention, the proper counter for a particular cut of cars is actuated, through selective circuits established by these repeater relays, each time a track relay is released due to the occupancy of a short track section in approach to this initial switch, this short track section being of a length such that it may be occupied by only one pair of wheels and the associated axle of the car at a time. Thus, in this first species, our invention provides an axle counting means from which a track fullness indication may be obtained on the basis that the great majority of cars being classified have but four axles. In a second species of our invention herein shown, a single counting device is actuated directly by the track relay for this short track section. A reset relay is then provided which is picked up at the end of each group of four counts inserted in the counting device, that is, each time the counting device has counted the four axles which usually signify one car. This reset relay resets the direct acting counting device to its zero position and at the same time actuates the proper track counting device through the selector circuits established by the repeater relays. Thus the counting device for a particular storage track is actuated once for each car entering that storage track. The fullness indication may then show the degree of track fullness or indicate the actual count of the number of cars entering that track.

Referring now to the drawings,

Fig. 1 shows in diagrammatic form apparatus embodying the first species of our invention, that is, an axle counting means for railway cars.

Fig. 2 shows diagrammatically a modification of the apparatus of Fig. 1 by which an actual count of the cars entering each storage track may be made.

In each of the drawings, similar reference characters refer to similar parts of the apparatus. Also, it is pointed out at this time that a suitable source of direct current energy is provided for the apparatus in each drawing, this power source being preferably a battery of proper voltage and capacity. For the sake of simplicity, however, this power source is not shown but its positive and negative terminals are identified by the conventional reference characters B and N, respectively. Furthermore, the contacts of slow acting relays are identified in a conventional manner by vertical arrows thereon, the direction of the arrow indicating the direction in which the relays are slow in operating.

Referring now to Fig. 1, there is shown at the top of this drawing in a conventional manner a group of eight storage tracks in a railway classification yard. It is assumed that these eight tracks are part of a larger number of storage tracks in a complete classification yard. It is also to be understood that our invention is not limited to groups of eight storage tracks, but may be applied to larger or smaller track groups, as will be obvious as the specification progresses. Cars or cuts of cars being classified move or approach this group of tracks from the left as is indicated by the arrow and pass over the initial switch of this group which is designated by the reference 1-8SW. From here the cars are routed to a pre-selected storage track over the various other switches, each of which is similarly designated as to the tracks which it controls. Throughout the specification, it will be considered that a switch positioned to divert a car to the left

is in its normal position while a switch is in its reverse position when it will divert a car to the right.

Switch 1-8SW is provided with a detector track section 1-8T. This track section is limited by the usual insulated joints which are shown conventionally by the short, heavy lines at right angles to the conventional single line showing of the track. This track section 1-8T is provided with a track circuit including a track relay. This track relay is designated by the reference 1-8TR and its connections to the rails are shown in a conventional way by a dotted line. Immediately in the approach to section 1-8T is a short track section here designated ZT. This track section is relatively short and is of a length such that only one pair of wheels and the associated axle of a car may occupy this track section at a time. It is thus similar to the track sections used for timing purposes in retarder speed control systems which are well known in the art. Actually, this section ZT may be the last such timing section in the speed control system for a group car retarder which would be the final retarder in the route to any one of the tracks in this particular group here shown. Track section ZT is likewise provided with a track circuit which includes a track relay ZTR. Again the connection of the track relay to the rails is shown in a conventional way. Each of these track relays is normally energized in the conventional manner through the rails by a suitable source of current, not shown, and becomes deenergized when any portion of the corresponding track section is occupied by a car or any part of a car.

As part of the apparatus of our invention, we provide a repeater of the track relays ZTR and 1-8TR which is designated by the reference character 1-8TP. This relay is energized, when either of the two previously mentioned track relays are deenergized and released, over an obvious circuit including back contacts 11 and 12, in multiple, of relays 1-8TR and ZTR, respectively. The use of this repeater relay in the general system of our invention will appear later in the specification. It is to be here noted that the control circuit for relay 1-8TR may be modified so that this relay releases in response to the occupancy of either section ZT or section 1-8T. The independent control of relay ZTR remains as shown. In this arrangement, relay 1-8TP would repeat only the release of track relay 1-8TR and would be thus energized only over back contact 11 of this latter relay. Also, it is obvious that section ZT may be eliminated entirely and relay ZTR replaced by any well known mechanical detection device such as a treadle or rail contactor, or by a radiant energy detection device such as a magnetic detector or a photoelectric cell.

The entire classification yard of which the group of tracks 1 to 8 form a part is assumed to be equipped with an automatic switching system of any type well known to the art. One such system is disclosed in the copending application for Letters Patent of the United States Serial No. 355,281, filed May 15, 1953, by Benjamin Mishelevich for Automatic Control of Railway Classification Yard Track Switches, now Patent No. 2,863,991, issued December 9, 1958. A similar system is described in the instruction pamphlet Manual 517, published in January 1953 by the Union Switch & Signal, Division of Westinghouse Air Brake Company, this manual being entitled "Union Automatic Switching for Classification Yards." For purposes of this description, it will be assumed that the switching system is similar to that described in either of these references. The details of the switching system are thus discussed herein only in sufficient detail to provide an understanding of the operation of the apparatus comprising our invention. Reference is here made to Manual 517 and/or Patent No. 2,863,991 for a complete description of the automatic switching system if desired.

As part of the automatic switching apparatus, each switch location in this yard has associated therewith one

or more route storage banks. Each such storage bank includes a number of switch control storage relays, a storage transfer relay, and a storage detector relay. Thus the final or A storage bank for switch 1-8SW includes the switch control storage relays A1W to A4W, inclusive, the storage transfer relay AST, and the storage detector relay ASD. As indicated on the drawing, relay AST is energized to initiate a storage transfer into bank A at switch 1-8SW and remains energized during the complete transfer action. Relay AST is released when the storage transfer action is completed and cannot be reenergized until bank A is again free of a route storage.

Storage detector relay ASD is energized when a route is to be transferred into bank A and stored therein. This relay is energized by a circuit extending from terminal B over front contact 13 of relay AST, the winding of relay ASD, and back contacts 14 and 15 of the storage transfer relays 1-4ST and 5-8ST, respectively, to terminal N. Transfer relays 1-4ST and 5-8ST are associated, respectively, with the route storage banks for switches 1-4SW and 5-8SW. Back contacts 14 and 15 are included in the energizing circuit for relay ASD to illustrate, in a conventional way, that a route storage cannot be transferred into bank A unless the proper conditions exist, that is, no similar transfer of another route storage from bank A into a succeeding storage bank is in progress. These back contacts also provide a means of interrupting the stick circuit for relay ASD at the proper time, as will be explained shortly. Also, the conventional dotted line between terminal B and front contact 13 of relay AST is intended to portray circuit connections of the switching system not here involved which provide other features such as individual and general cancellation of route storages. A more complete understanding of the energizing circuit for relay ASD and the details of operation may be had by referring to the previously mentioned Patent 2,863,991 or Manual 517. Relay ASD is further provided with a stick circuit which includes its own front contact 16 to by-pass front contact 13 of relay AST, this latter contact opening as soon as the transfer action into bank A is complete. Relay ASD, once energized as a route is stored in the A bank, remains energized until this route is transferred to a succeeding storage bank, the stick circuit being interrupted at that time by the energization of either relay 1-4ST or relay 5-8ST. It is to be noted that relay ASD has slow release characteristics so that, although the relay is deenergized by the opening of back contact 14 or 15, its front contacts remain closed until the route information is transferred.

Sufficient switch control storage relays are provided in this A bank to provide one relay for each switch in any possible route to a storage track which passes over switch 1-8SW. In other words, there must be a switch control storage relay for each of the maximum number of switches, including switch 1-8SW, in any route which may be stored in bank A. Each of these switch control storage relays is energized when the corresponding switch is to be operated to its reverse position. Accordingly, each relay is released when the corresponding switch is to be operated to its normal position. Thus the combination of energized relays of the group A1W to A4W, inclusive, determines the route which the corresponding car will follow as it passes over switch 1-8SW and the other switches associated with this group of storage tracks. Although only four switch control storage relays are here shown for bank A, it is to be understood that other storage track groups, even those having eight tracks, may require a different number of such relays in the A bank for the initial switch, the number of relays used being determined by the actual physical arrangement of the tracks and switches. Our invention is not limited to any particular number of switch control storage relays, but may be adapted to any arrangement, as will be apparent as the specification progresses.

The energized combination which these switch control storage relays assume for any particular cut of cars is transferred into this bank from a similar preceding storage bank, such as the relays in bank B associated with the same switch. The switch control storage relays in such a preceding bank are shown conventionally in Fig. 1 by a single relay symbol and their contacts are designated by the reference characters B1W to B4W, inclusive. As explained in the previously mentioned switching system references, the energized combination is initially determined as the result of a selection by the yard operator of a route for the particular cut of cars as it leaves the hump, the stored route then being transferred in sequence as the corresponding cars move from switch to switch in the yard along their selected route. The switch control for each switch is dropped from the combination as the route storage transfers from the corresponding A bank. Thus the energizing circuit for relay A1W in this A bank for switch 1-8SW may be traced from terminal B over front contact 17 of relay B1W, front contact 18 of relay AST, the winding of relay A1W, and front contact 19 of relay ASD to terminal N. When relay A1W picks up, it establishes a stick circuit which includes its own front contact 20, the relay winding, and front contact 19 of relay ASD, so that the switch control storage relay if energized remains held up while the route remains stored in this particular A bank. Each of the other switch control storage relays in bank A is energized over a similar circuit controlled, respectively, by relays B2W, B3W, and B4W and, if energized, is held energized by a stick circuit established at its own front contact. It is to be seen, therefore, that when a route storage is transferred into this A bank, the energized combination of the switch control storage relays B1W to B4W in the preceding bank determines the corresponding energized combination which relays A1W to A4W assume upon completion of the storage transfer.

Our invention adds a repeater relay for each of the switch control storage relays of this A bank. These repeater relays are here designated by the reference characters A1P, A2P, A3P, and A4P, respectively. Each of these repeater relays is energized when the corresponding switch control storage relay becomes energized. For example, the energizing circuit for relay A1P may be traced from terminal B at front contact 21 of relay A1W through back contact 22 of relay 1-8TP and the winding of relay A1P to terminal N. When a car is occupying either of the track sections ZT or 1-8T, a stick circuit is established for relay A1P, if previously energized, which may be traced from terminal B at front contact 23 of relay A1P over front contact 22 of relay 1-8TP and the winding of relay A1P to terminal N. The repeater relays are made slightly slow release so that, if energized, they will remain held up during the transfer time of the contacts of relay 1-8TP. This stick circuit is necessary since the route stored in the switch control storage relays A1W to A4W, inclusive, is transferred to the succeeding storage bank along the selected route as soon as the corresponding car or cut of cars occupies track section 1-8T. As will appear later, the repeater relays must remain energized in whatever combination selected until the entire car or cut of cars has passed over track section ZT so that a complete count may be entered in the proper counting device. The stick circuit for relay A1P assures that this relay, if initially energized, will thus remain energized until the car has cleared section ZT. Each of the repeater relays has similar energizing and stick circuits, as will be obvious from an inspection of the drawing, and it is unnecessary to trace these circuits in detail.

Our invention also adds a repeater relay of the storage detector relay ASD, this repeater relay being designated by the reference character ASDP. This relay is energized at any time that a route is stored in bank A and is

held energized until the associated cut of cars has cleared the detector track section. The energizing circuit for relay ASDP may be traced from terminal B over front contact 24 of relay ASD, back contact 25 of relay 1-8TP, and the winding of relay ASDP to terminal N. When relay 1-8TP is energized and picks up, a stick circuit is completed for relay ASDP which includes front contact 26 of this latter relay and front contact 25 of relay 1-8TP. As will appear shortly, relay ASDP must be picked up for a count to be entered in any one of the counting devices and thus prevents the entry of a count during a reverse movement out of the storage tracks over switch 1-8SW.

One counting device is provided for each storage track in the group shown at the top of the drawing. These devices are shown at the right of Fig. 1 by conventional symbols with a number inside each symbol to indicate the storage track with which that particular counter is associated. Each of these counters is an electrical counting device and may be a Veeder counter, a stepping switch, a magnetic impulse counter, or any other similar type of counter which will advance one count or one step during each period of energization of the counter. It is to be understood that any such counter will work equally well in the system of our invention shown in Fig. 1 and the use of any one of these types or designs of counting devices is anticipated.

The particular counter in which a cut of cars moving over switch 1-8SW is to be recorded is selected by the repeater relays in accordance with the existing energized combination of these four relays, that is, in accordance with the track to which the particular cut of cars is being routed. The selected counter is then energized each time relay ZTR releases and thus, as previously explained, counts each axle of the car or cut of cars passing over the initial switch. For example, if a car is routed to track 1, each switch in the route must occupy its normal position so that all switch control storage relays and, correspondingly, all their repeater relays are de-energized. Counter 1 will then be energized each time relay ZTR releases through a circuit traced from terminal B over back contact 27 of relay ZTR, front contact 28 of relay ASDP, which assures that a route has been stored for this particular movement over the switch, back contact 29 of relay A1P, back contact 30 of relay A2P, back contact 31 of relay A3P, back contact 32 of A4P, and the winding of counter No. 1 to terminal N. Each axle of this particular cut of cars will thus be recorded by counter No. 1. If the cut of cars is routed to track 4, the circuit for counter No. 4 would include back contact 27 of relay ZTR, front contact 28 of relay ASDP, back contact 29 of relay A1P, front contact 30 of relay A2P, and the winding of counter No. 4. Similarly, if a cut is designated for track 7, the energizing circuit for counter No. 7 would include, in addition to back contact 27 and front contact 28 previously mentioned, front contact 29 of relay A1P, front contact 33 of relay A2P, front contact 34 of relay A3P, and back contact 35 of relay A4P. Similar energizing circuits for the remaining counters may be traced, but a detailed description is not considered to be necessary, as these circuits are obvious from an inspection of the drawing when taken in connection with the previous circuit descriptions.

The counters 1 to 8, inclusive, may then be used to activate some type of a visual track fullness indicator. The circuit arrangement for this control is not here shown as the actual details would depend upon the type of counter in service. One possible method for a particular type counter will be discussed later in connection with the description of the second species of our invention. The series of counters may also be used to provide a track fullness factor which may be recorded in a storage device for use in the automatic speed control system associated with the car retarders used in this classifica-

tion yard. In providing a visual track fullness indication or a track fullness storage factor, proper consideration must be taken that the actual count recorded in any one of these counters is an axle count and that this total count must be divided by a factor of four to obtain the number of cars occupying any particular storage track.

Referring now to Fig. 2 which shows a second form of our invention, the apparatus illustrated therein elaborates on the system of Fig. 1 to provide an actual car count recorded in the counting device associated with each storage track. Basically, the apparatus is similar to that shown in Fig. 1 and already discussed. For example, the same group of storage tracks 1 to 8 is involved in the counting system. The repeater relays A1P to A4P of the switch control storage relays are shown, but without the control circuits since these are identical with those already shown and discussed in connection with Fig. 1. Likewise, track relay ZTR, track repeater relay 1-8TP, and storage detector repeater relay ASDP are identical with the similar designated relays shown in Fig. 1 and are similarly controlled. Thus, all these circuits have been omitted from Fig. 2 for simplicity and to eliminate any repetition of the discussion.

In the system illustrated in Fig. 2, relay ZTR controls directly an auxiliary or general counting device designated by the reference character GMC. For purposes of showing actual details of the manner of providing the car count, this counting device is here shown as being of the magnetic impulse counter type. It will be herein assumed for purposes of this description that this magnetic impulse counter is similar to those shown and described in any of the Letters Patent of the United States Nos. 2,487,015, 2,538,817, and 2,538,819 granted to John I. Bellamy for Electromagnetic Counting Devices, the earliest patent being issued November 1, 1949, and the latter two patents being issued January 23, 1951. It is to be understood, of course, that other types of counting devices may be used with the apparatus illustrated in Fig. 2 and that our invention is not limited to the use of such magnetic impulse counters as here illustrated. The other types of counting devices previously mentioned may be adapted to provide an actual car count by properly designing the circuit arrangement according to well known principles.

To provide an understanding of the operation of the actual detailed arrangement shown in Fig. 2, the magnetic impulse counter GMC as here shown has two windings and is provided with 10 individual armatures, each armature controlling a lower make and an upper break contact. These armatures are operated sequentially in response to electrical impulses or pulses of current flowing through the upper winding. This operating winding of the magnetic impulse counter is designated by an arrow pointing upward inside the symbol for that winding. Only one armature is operated with each pulse of current flowing through this upper winding, the armatures being interlocked in such a fashion that a pulse of current operates a particular armature and at the same time conditions the next armature in the sequence to operate on the next pulse of current. However, only a single pulse of current is required to operate the first armature. Once actuated, each armature is held in its operated position by residual magnetism supplied in some models from a permanent magnet provided in the impulse counter. As shown in Fig. 2, the armatures operate sequentially in ascending order of the numbers used as reference characters for the contacts, that is, from 1 to 10 in order. In magnetic impulse counter GMC, and in counters 4MC1 and 4MC2 to be discussed later, certain of the armatures in the sequence have been omitted from the detailed showing since they do not specifically enter into the operation of the circuits. These omissions are indicated by conventional dotted lines in the connections shown, as will be apparent during the following discussion.

In each of the magnetic impulse counters, release of the actuated armatures is accomplished by energizing a second or lower winding which acts to neutralize the residual magnetism holding the armatures in their operated position. In the drawing, this release winding is designated by an arrow pointing downward inside the symbol for the winding. Restated in another fashion, the first pulse of current flowing through the upper winding of one of the magnetic impulse counters actuates the No. 1 armature to open its upper contact and close its lower contact. This pulse also conditions the No. 2 armature to operate on the next pulse of current. However, the No. 2 armature cannot be operated by this initial pulse of current which operated the No. 1 armature. The second pulse of current flowing through the upper winding of the counter then causes the No. 2 armature to operate, similarly opening its upper contact and closing its lower contact, and conditions the No. 3 armature to operate on the succeeding pulse. Once operated, the No. 1 and No. 2 armatures are held in their operated position by residual magnetism until the impulse counter is released by a pulse of current flowing through the lower winding.

Similar magnetic impulse counters in pairs are used as the counting device for each storage track. For the sake of simplicity, only the pair for track 4 is shown in Fig. 2. This pair is the previously mentioned magnetic impulse counters 4MC1 and 4MC2.

The apparatus of Fig. 2 also includes a reset relay 25 for each counting device. For example, the general reset relay GRS is associated with magnetic impulse counter GMC. Relay GRS is energized during normal operation over a first pickup circuit traced from terminal B over upper contact 5 and lower contact 4 of counter GMC and the winding of relay GRS to terminal N. A second pickup circuit, which is effective only when relays ASDP and 1-8TP are released, may be traced from terminal B through back contact 36 of relay ASDP, back contact 37 of relay 1-8TP, any one of three paths 30 including, respectively, upper contact 2 and lower contact 1, upper contact 3 and lower contact 2, or upper contact 4 and lower contact 3, all of counter GMC, and the winding of relay GRS to terminal N. One of the multiple paths through the contacts of counter GMC in this circuit network will be closed, as is obvious, if one, two, or three counts remain stored in the impulse counter. A stick circuit for relay GRS which is effective at certain times includes back contact 27 of relay ZTR and front contact 38 of relay GRS. At other times, as will appear later, relay GRS is provided with a retardation circuit which includes back contact 39 of relay 1-8TP and a resistor 40, this resistor being connected in shunting relation with the winding of relay GRS when back contact 39 is closed. When relay GRS is energized and picks up, the closing of its front contact 41 completes a circuit through the lower winding of counter GMC which causes the counter to reset to its zero position, that is, with all armatures released and all lower contacts open.

The reset relay 4RS is used to reset impulse counter 4MC1 associated with storage track 4. The reset circuit through the lower winding of counter 4MC1 is completed at front contact 42 of relay 4RS when this latter relay is energized and picks up. When relay 4RS picks up, it also completes a circuit which drives counter 4MC2 to advance one count in its cycle of operation. This circuit may be traced from terminal B over front contact 43 of relay 4RS through the upper winding of counter 4MC2 to terminal N. Relay 4RS is provided with an energizing circuit which, as shown, is completed from terminal B over lower contact 10 of counter 4MC1 through the winding of relay 4RS to terminal N. However, it is obvious that this energizing circuit may be connected to any one of the lower contacts of counter

4MC1 so that relay 4RS may be energized at any selected point in the cycle of operation of counter 4MC1.

Counter 4MC2 is reset by a manual operation only, and in conjunction with this, counter 4MC1 will be reset at the same time. The actual circuit arrangement for this is not shown in Fig. 2, but may be similar to that shown for the magnetic impulse counters in the previously mentioned copending application, Serial No. 564,027. Briefly, to manually reset counters 4MC1 and 4MC2, energy is applied over contacts of a manually operated push button or lever to wires 44 and 45 and from these wires to the lower windings of the two impulse counters, causing each counter to reset to its zero position with all of the lower contacts open. This manual reset action is used to reset the counters when the associated storage track is cleared of all, or at least a portion, of the cars which have entered that track. In the event that not all of the cars are cleared from the associated track, a count corresponding to those cars remaining in the track may be manually entered in counter 4MC1 by operating the previously mentioned push button or lever to a second position to apply energy to wire 46 and thence over back contact 47 of relay 4RS to the upper winding of counter 4MC1. As many counts as desired may be entered manually in this fashion.

We shall now describe the operation of the system illustrated in Fig. 2. Each time relay ZTR is released and closes back contact 27, the energizing circuit for counter GMC is completed, this circuit also including back contact 48 of relay GRS. At this time, with relay 1-8TP picked up to open back contact 37 and, if a route has been stored in bank A, relay ASDP picked up to open back contact 36, the second energizing circuit for reset relay GRS is open and this relay is not energized during the first three counts entered in counter GMC. When a fourth count is entered in counter GMC by the fourth successive release of relay ZTR, the previously traced first energizing circuit for relay GRS, including lower contact 4 of counter GMC, is completed and this relay picks up. The closing of front contact 41 of relay GRS resets counter GMC to its zero position, as previously explained. Relay GRS is held energized at this time, by the stick circuit including its own front contact 38, until relay ZTR again picks up. This allows sufficient time for counter GMC to be reset.

When relay GRS picks up, it also completes a circuit for energizing counter 4MC1, assuming for purposes of this explanation that the car or cut of cars is being routed to track 4. This circuit may be traced from terminal B at front contact 49 of relay GRS over front contact 28 of relay ASDP, which assures that a route has been stored for the car passing over switch 1-8SW, back contact 29 of relay A1P, front contact 30 of relay A2P, back contact 47 of relay 4RS, and the upper winding of counter 4MC1 to terminal N. This energization of counter 4MC1 causes it to advance one count in its cycle. Thus relay GRS energizes counter 4MC1 once for each four counts entered into general counter GMC by track relay ZTR. In other words, each count entered into counter 4MC1 represents one car under most operating conditions since, as previously mentioned, the great majority of railway cars handled in a classification yard have but four axles. It is obvious, if the car had been routed to another storage track, that the first impulse counter associated with that track would be energized in a similar manner over a circuit selected by the switch control storage repeater relays A1P to A4P, inclusive, as was discussed in connection with Fig. 1.

As shown in Fig. 2, at the end of a complete cycle of operation of counter 4MC1, that is, at the end of ten counts, relay 4RS is energized in a manner previously explained. Also as mentioned hereinbefore, it is obvious that relay 4RS may be energized at the end of any selected count less than ten by connecting its energizing circuit to the lower contact of counter 4MC1 corresponding to the selected count. When relay 4RS picks up, it energizes the

upper winding of counter 4MC2 and resets counter 4MC1, both operations having been previously explained. Thus one count is entered in counter 4MC2 for every ten counts, that is, for every ten cars counted by counter 4MC1. Connections from the lower contacts of counter 4MC2 may be made to any type of a visual track fullness indicator or track fullness storage device as desired in order to provide the necessary track fullness information for the operation of the speed control system of the car retarders, as was previously mentioned.

It may occur in the operation of the system that a car having more than four axles, for example, six axles, will pass over switch 1-8SW or that poor shunting by a pair of wheels of an ordinary car will fail to release relay ZTR during the passage of one axle through track section ZT. In this event, one, two, or three counts remain stored in general counter GMC when the car or cut of cars leaves detector track section 1-8T. As soon as the car leaves section 1-8T, relay 1-8TP is deenergized and releases. This interrupts the stick circuit for relay ASDP and, if no succeeding route storage has been transferred into bank A, relay ASDP also releases. The closing of back contacts 36 and 37 of relays ASDP and 1-8TP, respectively, completes the second energizing circuit for reset relay GRS which immediately picks up. The closing of front contact 41 of relay GRS energizes the reset winding of counter GMC, which resets to its zero position thus erasing the partial count stored therein. This also interrupts the energizing circuit for relay GRS. However, since back contact 39 of relay 1-8TP is closed at this time, the retardation circuit including resistor 40 is effective to hold relay GRS with its front contacts closed for a sufficient period to assure that counter GMC completely resets to its zero position. This clears any counts improperly stored in counter GMC. It is to be noted that, during the regular counting operation, the retardation circuit for reset relay GRS is not needed since its stick circuit will hold the relay energized for a sufficient period to reset counter GMC prior to the initiation of the succeeding counting operation.

It is to be understood, however, that the clearing of improperly stored counts from counter GMC does not necessarily occur immediately after the cut which caused the storage of the partial count clears section 1-8T. If a new route storage for a succeeding cut of cars has been transferred into bank A while the cut being counted still occupies section 1-8T, relay ASD will be held energized by its stick circuit. Thus, when relay 1-8TP eventually releases and interrupts, at its front contact 25, the stick circuit for relay ASDP, the energizing circuit for this latter relay is completed almost immediately at back contact 25 since front contact 24 of relay ASD is already closed. Relay ASDP is sufficiently slow release to bridge the transfer time of contact 25, and therefore does not release. Under these conditions, the second energizing circuit for relay GRS is not completed, since back contact 36 of relay ASDP remains open. However, the proper conditions, that is, bank A empty when sections 1-8T and ZT are free, will occur with sufficient regularity that the second energizing circuit for relay GRS will be completed within a reasonable time after each improper or partial count storage occurs and the system will be cleared frequently enough to maintain an accurate count.

It is thus to be seen that the system of our invention provides a means in a railway classification yard for accurately counting the number of cars entering each storage track. This system is relatively simple and inexpensive to provide since it uses existing automatic switching circuits as the principal control means of the system. In other words, the counting device for each track is selected through the routes already stored in the automatic switching circuits. In addition, only one actuating means is used for the counters for each group of storage tracks. It is further to be seen that the system of our invention prevents the counters from

being actuated during reverse movements from the storage tracks over the entrance switches. The counts recorded in the various counters may be used to provide a visual track fullness indication or may be used to provide a track fullness storage factor which can be further used in an automatic speed control system. Finally, the system of our invention is not limited to a particular type of counter, but various types may be used with equal facility to record the car counts provided by the system of our invention.

Although we have herein shown and described but two forms of apparatus for a railway car counting system embodying our invention, it is to be understood that various changes and modifications may be made therein within the scope of the appended claims without departing from the spirit and scope of our invention.

Having thus described our invention, what we claim is:

1. In a railway classification yard equipped with an automatic switching system for routing cars into the storage tracks, said system including at least one route storage relay bank for each track switch, each said relay bank including a plurality of switch control storage relays one for each track switch in any possible route including the associated switch, said storage relays in the relay bank for each switch being controlled by said switching system to be energized into different energized combinations according to the selected route for the next approaching car, the combination comprising, a plurality of repeater relays one for repeating at times each switch control storage relay in the final bank for the initial switch governing routes into a particular group of storage tracks, a plurality of electrical counting devices one for counting the axles entering each storage track of said particular group, a track relay having connections to the track at said initial switch to be operated in response to the passage of each axle of a car approaching said initial switch, energizing circuits including energized position contacts of the storage relays of said final bank and connected to energize said repeater relays in a combination corresponding to the energized combination of said final bank storage relays, stick circuit means controlled by the occupancy of the track section including said initial switch and connected for maintaining energized the existing energized combination of said repeater relays while a car passes over said initial switch, and a circuit network including an operated position contact of said track relay, front and back contacts of said repeater relays, and said counting devices, said circuit network being effective to periodically energize the counting device corresponding to the pre-selected storage track for an approaching car to count the number of axles of that car.

2. At a railway track switch over which railway cars are selectively routed according to preselected routes to a plurality of storage tracks, car counting apparatus comprising, a plurality of storage repeater relays energizable in any one of a plurality of energized combinations according to the preselected route stored at said switch for an approaching car, an electrical counting device operable to advance one count for each period of energization for counting the cars entering each storage track, another relay connected to be responsive to the occupancy of the track by a car approaching said switch to close a contact, and a circuit network including front and back contacts of said repeater relays, said contact of said other relay, and said counting devices to energize the counting device associated with the storage track preselected for a car passing over said switch to record that car.

3. At a railway track switch over which railway cars are selectively routed according to preselected routes to a plurality of storage tracks, a car counting arrangement to record the number of cars routed to each of said storage tracks, said counting arrangement comprising

5 an electrical counting device operable to advance one count for each period of energization for counting the cars entering each said storage track, a plurality of storage repeater relays energizable into a different energized combination to represent each possible route over said switch, circuit means responsive to the preselected route for energizing said repeater relays in the combination representing the preselected route for each approaching car, and an energizing circuit network including said counting devices, a contact closed in response to the passage of each car approaching said switch and front and back contacts of said repeater relays to energize the counting device for the track represented by the existing energized combination of said repeater relays to record the approaching car.

10 4. At the initial track switch for a particular group of storage tracks in a railway classification yard equipped with an automatic switching system, said system having at least one storage relay bank at each switch to store the preselected route for the next approaching car, the combination comprising, a plurality of storage repeater relays energizable in a different energized combination to represent each possible route over said switch, an electrical counting device representing each track 15 of said group, an auxiliary counting device, each said counting device normally occupying a zero position and adapted to advance one count during each period of energization, a reset relay, a normally open contact having connections to the track in approach to said switch so as to be closed in response to the passage of each axle of a car approaching said switch, circuit means controlled by the storage relay bank and by the unoccupied condition of the track section including said initial switch for energizing said storage repeater relays 20 in an energized combination representing the preselected route stored in said storage relay bank for the next approaching car, stick circuit means controlled by the occupancy of said track section for holding said repeater relays in the existing energized combination while the 25 corresponding car is passing over said switch, an energizing circuit for said auxiliary counting device including said normally open contact, a reset circuit for said auxiliary counting device including an energized position contact of said reset relay, said reset circuit being 30 effective when completed to reset said auxiliary counting device to its zero position, an energizing circuit for said reset relay including a contact of said auxiliary counting device closed after a preselected number of counts, and other energizing circuits one for each track 35 counting device, each said other circuit including another energized position contact of said reset relay and selected repeater relay contacts closed in series only when said repeater relays are energized in the combination 40 representing the route to the associated storage track.

45 5. In combination, a plurality of electrical counting devices, operable to advance one count of each period of energization, one for each track of a group of storage tracks in a railway classification yard, a plurality of 50 storage repeater relays energizable into a different energized combination to represent each possible route over the initial switch into said group, an auxiliary counting means having connection to the track in approach of said initial switch for controlling a normally open contact, to close once during the passage of each car over said switch; energizing circuit means controlled by preselected route storage for energizing said repeater relays in a particular combination representing the route to be followed by the next approaching car, stick circuit 55 means controlled by the occupancy of the track at said switch for maintaining the existing energized combination of said repeater relays while the corresponding car passes over said initial switch, and an energizing circuit for each counting device including said contact of said auxiliary counting means, another contact closed only when 60 70 75

a preselected route is stored for an approaching car, and contacts of said repeater relays closed in series to complete the circuit only when the existing energized combination of said repeater relays represents the route to the storage track associated with that counting device, each energizing circuit being effective to record in the corresponding counting device all cars routed to the associated storage track.

6. At the initial track switch for a particular group of storage tracks in a railway classification yard equipped with an automatic switching system, said system having at least one storage relay bank at each switch to store the preselected route for the next car approaching over the lead track to said initial switch, the combination comprising, a plurality of storage repeater relays energizable in a different combination to represent each possible route over said switch, an electrical counting device for each track of said group, an auxiliary counting device, each said counting device normally occupying a zero position and being adapted to advance one count during each period of energization, a reset relay, a normally open contact having connections to the lead track in approach to said switch so as to be closed in response to the passage of each axle of a car approaching said switch, circuit means controlled by said automatic switching system for energizing said storage repeater relays in the combination corresponding to the preselected route stored in said storage relay bank, stick circuit means controlled by the occupancy of said lead track for holding said repeater relays in the existing energized combination while the corresponding car is passing over said switch, an energizing circuit for said auxiliary counting device including said normally open contact, a reset circuit for said auxiliary counting device including an energized position contact of said reset relay, said reset circuit being effective when completed to reset said auxiliary counting device to its zero position, a first energizing circuit for said reset relay including a contact of said auxiliary counting device closed after a preselected number of counts, a second energizing circuit for said reset relay including a contact closed only when no car is passing over said switch and contacts in multiple of said auxiliary counting device which are closed one at a time for each count less than said preselected number, said second energizing circuit being effective to energize said reset relay when an incomplete count remains in said auxiliary counting device after a car passes over said switch, and other energizing circuits one for each track counting device, each said other circuit including another energized position contact of said reset relay and selected repeater relay contacts closed in series only when said repeater relays are energized in the combination representing the storage track corresponding to that counting device.

7. At the initial track switch for a particular group of storage tracks in a railway classification yard equipped with an automatic switching system, said system having at least one storage relay bank at each switch to store the preselected route for the next car approaching said initial switch over the lead track, the combination comprising, a plurality of storage repeater relays energizable in a different energized combination to represent each possible route over said switch, a track repeater relay having connections to said lead track to be energized when a car is passing over said switch, a storage detector repeater relay, an electrical counting device for each track of said group, an auxiliary counting device, each said counting device normally occupying a zero position and being adapted to advance one count during each period of energization, a reset relay, a normally open contact having connections to the lead track and closed in response to the passage of each axle of a car approaching said switch, an energizing circuit for said storage detector repeater relay including a back contact of said track repeater relay and another contact

closed only when a preselected route is stored in said storage bank, a stick circuit for said storage detector repeater relay including a front contact of said track repeater relay, other energizing circuits including other back contacts of said track repeater relay and contacts controlled by said storage relay bank to energize said storage repeater relays in the energized combination corresponding to the preselected route stored in said storage bank, other stick circuits including other front contacts of said track repeater relay to hold said storage repeater relays in the existing energized combination, an energizing circuit for said auxiliary counting device including said normally open contact, a reset circuit for said auxiliary counting device including an energized position contact of said reset relay, said reset circuit being effective when completed to reset said auxiliary counting device to its zero position, an energizing circuit for said reset relay including a contact of said auxiliary counting device closed after a preselected number of counts; a second energizing circuit for said reset relay including a back contact of said storage detector repeater relay, another back contact of said track repeater relay, and contacts in multiple of said auxiliary counting device which are closed one at a time for each count less than said preselected number; said second energizing circuit being effective to cause said auxiliary counting device to be reset when a count is stored therein with no route stored in said storage bank and no car passing over said switch, and an energizing circuit for each track counting device including another energized position contact of said reset relay, a front contact of said storage detector repeater relay, and selected storage repeater relay contacts closed in series only when said storage repeater relays are energized in the combination representing the associated track, to periodically energize the corresponding counting device to count each car routed to the associated storage track.

8. In a railway classification yard equipped with an automatic switching system for routing cars into the storage tracks in accordance with preselected routes, said system including at least one route storage relay bank for each track switch, each said relay bank including a plurality of switch control storage relays one for storing the position of each track switch in any possible route including the associated switch, said storage relays in the final bank for each switch being controlled by said switching system to be sequentially energized into different energized combinations according to the selected route for the next approaching car, track fullness measuring apparatus for each storage track of a particular group of tracks in said yard comprising, a plurality of storage repeater relays one for repeating at times each switch control storage relay in the final bank at the initial switch for said particular group of tracks, an electrical counting device for each track of said particular group and operable to advance one count during each period of energization, a track relay connected to the rails at said switch and responsive to each axle of a car routed over said initial switch to periodically close a normally open contact, energizing circuit means controlled by said storage relays of said bank for energizing said repeater relays in different combinations corresponding to the sequence of energized combinations of said final bank storage relays, stick circuit means controlled by the occupancy of the track section including said initial switch for maintaining the existing energized combination of said repeater relays while a car passes over said initial switch, and another circuit network including said track relay contact, the counting devices for each storage track of said particular group, and front and back contacts of said repeater relays closed to complete different paths to select a different counting device for each energized combination of said repeater relays to periodically energize the selected count-

ing device to record the fullness of each storage track of said particular group.

9. In a railway classification yard equipped with an automatic switching system for routing cars into the storage tracks in accordance with preselected routes, said system including at least one route storage relay bank for each track switch, each said relay bank including a plurality of switch control storage relays one for storing the position of each track switch in any possible route including the associated switch, said storage relays in the final bank for each switch being controlled by said switching system to be sequentially energized in different energized combinations according to the selected route for the next approaching car, track fullness measuring apparatus for a particular track in said yard comprising, an electrical counting device associated with said particular track and operable to advance one count during each period of energization, said counting device indicating by the position to which advanced the fullness of said particular track, a plurality of 20 storage repeater relays one for repeating at times the position of each switch control storage relay in the final relay bank for the initial switch of the track group including said particular track, energizing circuit means controlled by the storage relays of said final relay bank 25 for sequentially energizing said repeater relays in dif-

ferent combinations corresponding to the sequence of energized combinations of the final bank storage relays for said initial switch, stick circuit means controlled by the occupancy of the track section including said initial switch for maintaining the existing energized combination of said repeater relays while a car passes over said initial switch, and an energizing circuit for said counting device including a contact periodically closed in response to the passage of each car approaching said initial switch and contacts of said repeater relays closed in a series circuit only when the energized combination of said repeater relays represents the route to said particular track.
